(57) **CLAIM**

The ornamental design for the handle for a tool caddy, as shown and described.

DESCRIPTION

FIG. 1 is a front view of a handle for a tool caddy, shown with environment, showing my new design.

FIG. 2 is a right side view thereof.

FIG. 3 is a top view thereof.

FIG. 4 is a bottom view thereof.

FIG. 5 is a perspective view thereof.

FIG. 6 is a front view thereof.

FIG. 7 is a right side view thereof.

FIG. 8 is a top view of the handle for a tool caddy, shown in isolation; and,

FIG. 9 is a bottom view thereof.

The broken lines in the figures are included for the purpose of illustrating environmental structure and form no part of the claimed design.

1 Claim, 6 Drawing Sheets
